Inventor.
William H. Bihn.

By: William C. Linton.

Attorney

UNITED STATES PATENT OFFICE.

WILLIAM H. BIHN, OF PETALUMA, CALIFORNIA.

EGG TRAY.

Application filed July 6, 1922. Serial No. 573,087.

To all whom it may concern:

Be it known that I, WILLIAM H. BIHN, a citizen of the United States of America, residing at Petaluma, in the county of Sonoma and State of California, have invented certain new and useful Improvements in Egg Trays; and I do hereby declare that the following is a full, clear, concise, and exact description of the same, such as will enable others skilled in the art to which it appertains to make and use the same.

This invention has reference generally to incubators and more particularly relates to an improved egg tray therefor.

It is the principal aim and object of this invention to provide a tray of the above character for use in connection with an incubator such as disclosed in my Patent Number 1,422,250, with a view particularly toward increasing the capacity of the incubator over that accomplished by the regular tray thereof.

As an additional and equally important object, the invention embraces the provision of a tray of improved construction wherein "traying" of the eggs is facilitated in that they may be placed therein when the tray is resting on a table or other support, and, as means is provided for each separate egg, the danger of the eggs toppling over is eliminated and in making tests any infertile egg may be removed without disturbing the remaining eggs.

More particularly this invention consists in the provision of an egg tray consisting of a perforate bottom and side and end walls, both of novel construction and shaped to support the bottom while the end walls also form supporting legs for maintaining the bottom in spaced relation to a support and in addition, are designed to accommodate the reinforcing rods which act to retain the side walls and bottom together.

Among the other aims and objects of the invention may be recited the provision of a device of the above mentioned character with a view to compactness and wherein the number of parts are few, the construction simple, the cost of production low and the efficiency high.

Further objects as well as the nature, characteristic features and scope of this invention will be more readily apparent from the following description taken in connection with the accompanying drawings

and pointed out in the claims forming a part of this specification.

The invention is clearly illustrated in the accompanying drawings, in which:

Figure 1 is a top plan view of the improved tray;

Figure 2 is a perspective thereof;

Figure 3 is a transverse section taken on the line 3—3 of Figure 1; and,

Figure 4 is a fragmentary longitudinal section taken on the line 4—4 of Figure 1.

Similar characters of reference are employed in all of the above described views to indicate corresponding parts.

Referring now more particularly to the drawings, there is provided the improved tray including a bottom 1 preferably formed from sheet metal, being a rectangular blank thereof and having its area provided with openings 2 of such size to receive and support an egg and being preferably square in outline. It is also preferred that the openings be arranged in rows parallel transversely and zig-zag longitudinally, as shown to advantage in Figure 1. The outer side and end portions of the bottom are bent outwardly and downwardly to form flanges 3, arranged at right angles to the under surface of the bottom for a purpose to appear.

Side walls 4 are now provided and like the bottom are preferably formed of sheet metal. In order to support the bottom in spaced relation to a main support (not shown) and at the same time allow for the proper reception of eggs in the openings 2, the lower portions of the side walls are folded upwardly and inwardly in slightly spaced relation to the main portions as at 5 to form supporting legs 6 and ledges 7 upon which rests the bottom, while the flanges 3 of the latter are accommodated in the spaces 5 and act to retain the bottom against the side walls.

End walls 8 are now employed being also desirably formed of sheet metal, and provided with attaching flanges 9 at their outer ends arranged to embrace the outer faces of the adjacent end portions of the side walls to which they are secured by suitable fasteners such as rivets 10. The upper edges of the walls 4 and 8 align and are substantially beaded as at 11 for reinforcing purposes and for facilitating the handling of the tray. The lower portions of the end

walls are bent inwardly and upwardly as at 12 in spaced relation to the main portions to form ledges 13 for the bottom and to leave spaces 14 for the adjacent flanges 3.

5 In this connection, it is to be noted that the free edges of the flanges rest on the bend 12 to further increase the rigidity. If desired, solder 15 may be used to rigidly hold the ledge portions to the bottom.

10 With a view toward providing improved means for reinforcing the bottom and for locking the side walls and bottom together, a series of rods 16 are employed and are inserted through aligning openings 17 and 15 recesses 18 respectively in the main portions of the side walls, the side flanges 3, and in the ledge portions of the side walls, as shown in Figure 3.

It is believed in view of the foregoing description that a further detailed description of the invention is entirely unnecessary. Likewise it is believed that the advantages of the invention will be readily apparent.

I claim:

25 1. A tray of the character described including a perforate egg receiving and supporting bottom, side walls connected with the bottom and forming legs to support the bottom, end walls secured to the side walls, 30 and means passing through the side walls and bottom for securing the parts together and also serving to reinforce the bottom.

35 2. A tray of the character described, including a perforated egg receiving and supporting bottom, flanges depending from the edges of the bottom, side and end walls connected to each other, means on the inner faces of the walls for accommodating and retaining the flanges so as to support the

bottom, the side walls acting as supporting legs, and common means extending through the side walls and flanges for locking the same together and for reinforcing the bottom.

3. A tray including side and end walls connected with each other, the upper edges of the end walls aligning with the upper edges of the side walls and having their lower edges terminating short of the lower edges of the side walls, an egg receiving and supporting bottom, cooperative means on the bottom and on the walls for supporting the bottom in substantial alignment with the lower edges of the end walls, and common means for locking the walls and bottom together and for reinforcing the bottom.

4. A tray of the character described including a perforate egg receiving and supporting bottom provided with depending flanges at its edges, side and end walls connected to each other and having their lower portions bent inwardly and upwardly in slightly spaced relation to the main portions thereof and terminating in ledges for supporting the bottom, the flanges on the bottom being engaged in the spaces provided between the ledges and the main portions of the walls, the lower folded portions of the side walls constituting supporting legs, means for locking the side walls to the flanges consisting of rods extending transversely through the side walls and flanges and transversely beneath the bottom and contacting with the bottom for reinforcing purposes.

In witness whereof I have hereunto set my hand.

WILLIAM H. BIHN.
